UNITED STATES PATENT OFFICE.

DAVID I. GARRETSON, OF NEW YORK, N. Y.

HORSESHOE.

1,149,359.

Specification of Letters Patent.

Patented Aug. 10, 1915.

Application filed November 3, 1911. Serial No. 658,296.

To all whom it may concern:

Be it known that I, DAVID I. GARRETSON, a citizen of the United States, and a resident of the city, county, and State of New York, have invented certain new and useful Improvements in Horseshoes, of which the following is a specification.

My invention relates to improvements in horse shoes and the object thereof is to provide a shoe which will so grip the road as to prevent slipping even under extraordinary conditions, as when the road is wet or coated with ice or snow.

Another object of my invention is to construct a shoe for such purpose which will be very inexpensive to manufacture so that the cost will be as near as may be to the cost of the ordinary shoes in common use, but one which will wear longer.

My invention belongs to that class of shoe in which the shoe proper or frame, and the tread are formed separately and the tread secured to the frame. Various devices in this class have been proposed, one of which is shown in the U. S. patent to Hubner, No. 873,373, dated December 10, 1907, wherein the tread is formed separately from a number of strips of fabric of woven wire, which are inserted in and held by the shoe frame. The wires of the tread engage at their ends with the road surface and form the tread of the shoe.

The object of my present invention is to construct a shoe which will have even greater non-slipping qualities than the said Hubner shoe, but which will be much less expensive to manufacture. In the Hubner shoe it is necessary to form the inserted tread from a number of pieces of woven wire fabric which latter have to be woven more or less by hand from expensive material, whereas in my present shoe the tread may be very cheaply formed from common commercial metals. In the said Hubner shoe the number of wires which can be inserted in a given shoe are limited by the nature of the tread and the combined areas of the ends of the wires are therefore small, so that the shoe is not only expensive to make but its life is comparatively short.

I find it desirable to construct the shoe proper or frame and the tread separately, so that the tread may be tempered hard without tempering the frame, which, for practical reasons, should not be made too hard; and I also find it desirable to form the frame

and tread separately in order to construct a tread which will resist slipping in various directions and provide considerable wearing surface. I have therefore constructed a frame having a groove or channel extending around the greater portion of one face of the shoe and also having means for holding the tread against lateral strains: and I construct a separate tread from sheet metal by bending a strip or ribbon of comparatively thin metal in a zig-zag or serpentine formation. The separately formed tread is inserted into the channel of the frame so that its edge forms the tread of the shoe not only when first used, but also as the separately formed tread wears down during use. The interstices caused by the bending of the plate or sheet which forms the tread are preferably left open so that the edge of the tread, upon which the shoe rests will firmly grip the road surface at all times and prevent slipping.

I form the separate tread of a metal (preferably steel) high in carbon, while in a comparatively soft or annealed condition; I form the shoe proper or frame of a softer metal and then temper the tread (and preferably without hardening the frame) after the tread has been inserted in the frame. The tread will be tempered much harder than the frame owing to the fact that it is made of high carbon metal and the frame will not be rendered too hard or brittle for practical purposes.

Further details of my invention and the advantages thereof will appear hereinafter.

Figure 1, is a plan view of the under or tread side of a shoe embodying my improvements in which a portion of the tread is omitted to disclose the retaining channel. Fig. 2, is a cross section taken on the line 2—2 of Fig. 1, and Fig. 3, is a perspective view of a portion of the tread as shaped and ready for insertion into the channel.

The shoe proper or frame is shown at 1, and is preferably of the same general outline as an ordinary shoe, but in one face thereof I provide a channel 2, which is disposed around the shoe, preferably substantially the whole portion thereof. This channel is defined by inner and outer flanges 3 and 4. The nail holes 5, are arranged outside of the tread and near the outer rim of the shoe. Extending from the inner flange 3, are narrowing projections 6, which taper at each side 7: and projections 8, extend

upwardly from the flange 4, and taper on each side 9. The flanges 3 and 4, form the channel for the inserted tread and projections 6 and 8, rise above them and support the tread laterally but their top surfaces are small so that they will wear away fast when the tread is worn down to the level of their top surfaces, in order that these projections will not predominate as part of the tread and overcome the non-slipping action of the latter. The tread is constructed independently of this frame, and of a metal having a large percentage of carbon in order that it may be tempered to a considerable degree of hardness.

The tread 10, is formed of a strip of flat metal preferably of uniform thickness throughout and of a width sufficient to cause the same to project above the frame of the shoe when inserted on edge, and form a wearing tread for the shoe. I bend this plate 10, into such shape, while in its soft or annealed condition, that I am enabled to place a large quantity within the channel of the frame and provide an edge of such configuration that it will resist the slipping action of the shoe in all directions. Preferably the same is formed into a succession of reverse curves, forming loops arranged in close proximity to each other. I have shown the tread as constructed in this manner. Starting at the point 11, the plate curves into a loop 12, from whence the curve reverses at 13, and at the opposite side of the tread is formed another loop 14, in reverse direction to the first; from whence the plate curves reversely at 15, to the opposite side of the tread and a reverse loop 16, is formed: and so on until the plate has been formed long enough for one or more shoes. The general direction of the tread when thus formed is preferably straight, but in order to insert the tread in the channel 2, of the shoe, it is curved or arched to conform to the channel. The tread is inserted in the channel 2, as shown in Fig. 1, so that it lies edgewise or at right angles to the plane of the shoe, thus presenting its projecting edge as a wearing tread for the shoe. The natural resiliency of the tread when it is arched to place it in the channel causes it to bind against the flanges 3 and 4, and projections 6 and 8, and causes it to be held in place; but I prefer to use additional and inexpensive means for holding the tread in place. For this purpose I place small quantities of spelter 22, in the bottom of the channel 2, near the side walls thereof. When the tread has been formed and inserted into the channel 2, the entire shoe is heated above the melting point of spelter and preferably sufficiently to produce a blue temper in the tread; when the spelter will flux. After this the shoe is dipped in any suitable manner in order to temper the tread 10. Since the

tread has a high percentage of carbon and the shoe frame a very little or no carbon, the former will become very hard, while the frame will remain suitable for its purpose. When the spelter cools it forms a means for firmly holding the tread 10, to the interior of the channel 2. It will be noted that the lower wall or bottom 17, of the channel 2, is depressed or concaved toward the middle so that when the tread is seated therein it will rest against the sides 18, of the bottom and at 19 will be spaced therefrom. The purpose of this is to produce a certain amount of vertical spring in the tread to soften the shock upon the animal. The tread rests rigidly on the channel bottom at each side and as the tread wears away at each top side edge leaving it raised near the middle 21, the feature will become more pronounced.

It will be apparent that a shoe constructed in accordance with my invention will be durable and lasting since the active tread can be made very hard while the frame is not made brittle; while on the other hand the shoe can be very inexpensively made. Owing to the serpentine nature of the plate tread, which rests on its exposed edge slipping in all directions is prevented by the grip of the tread upon the road surface.

I have found that by curving the tread strip in the formation here shown I can get a very long strip of metal of a thickness which will lend itself readily to the bending operation, into a channel of given dimensions; and therefore, while preserving the advantages of a tread having open spaces, the total area of the plate is considerably greater than the total areas of the ends of the wires in a construction such as is shown in said Hubner patent and consequently the tread will have a longer life. The tread will remain in the channel with its edge exposed until the tread wears substantially away, and the projections 6 and 8, having a small area and being of softer metal, never predominate as the tread wears down to their level, sufficient to overcome the gripping action of the tread on the road, but wear down faster than the tread.

The projections 6 and 8, are shown disposed in a relatively staggered relation, but this feature is not *per se* here claimed as it forms the subject matter of an application filed by me on the 20th day of September 1911, and serially numbered 650378.

Having described my invention what I claim is:—

1. A horse shoe comprising a metallic frame having a channel extending substantially around one face of the shoe, and a separately formed tread consisting of a metal strap bent back and forth upon itself to form reversely arranged curved loops and intermediate reverse curves, said tread

being disposed edgewise in said channel whereby one edge thereof forms the wearing surface of the shoe, and secured in said channel by being brazed to the shoe, so that 5 the tread becomes an integral portion of the shoe.

2. A horse shoe comprising a frame having a channel extending substantially around one face of the shoe, and a separately formed tread consisting of a metal strip bent back and forth upon itself, and disposed in said channel whereby one edge 10 will form the tread surface of the shoe, the parts being so arranged that portions of the 15 bottom of the tread will rest on the bottom of said channel and the other portions thereof will be separated therefrom whereby the said tread will be resilient.

3. A horse shoe comprising a frame hav-

ing a channel extending substantially 20 around one face of the shoe, and a separately formed tread consisting of a metal strip bent back and forth upon itself, and disposed in said channel whereby one edge 25 will form the tread surface of the shoe, the bottom of said channel being concave whereby the said tread will rest on part of the bottom wall and be resiliently separated from the convex portion thereof, and spelter for securing the tread to the shoe 30 frame.

Signed at the city, county and State of New York, this 31st day of October 1911.

DAVID I. GARRETSON.
